UNITED STATES PATENT OFFICE.

JOHN HETHERINGTON, OF BENTON HARBOR, MICHIGAN, ASSIGNOR OF ONE-HALF TO
DAVID R. JONES, OF BENTON HARBOR, MICHIGAN.

FAUCET.

1,091,135.

Specification of Letters Patent. Patented Mar. 24, 1914.

Application filed September 27, 1911. Serial No. 651,496.

To all whom it may concern:

Be it known that I, JOHN HETHERINGTON, a citizen of the United States, residing at Benton Harbor, in the county of Berrien 5 and State of Michigan, have invented certain new and useful Improvements in Faucets, of which the following is a specification.

This invention relates to faucets for drawing off water for drinking and other purposes, and the improvement consists in combining in such a faucet a hygienic drinking or bubbling cup and a drawing-off outlet, or tap.

15 A further object is to provide simple means by which the height of the bubbling fountain may be adjusted, not only with reference to the general average pressure of the water in the mains, but also with reference 20 to temporary variations in pressure.

In the accompanying drawings Figure 1 is a central, vertical section of one form of faucet embodying the features of my invention. Fig. 2 is a top plan of the faucet, and 25 Fig. 3 is a fragmental longitudinal section along the line 3 of Fig. 1. Fig. 4 is a fragmental elevation of the valve member 1.

The device as indicated consists of the 30 taper valve member 1 fitting within the barrel ref 15, said valve member having a handle 2, a passage 3 with an opening or port 4 through which water may flow from the intake pipe 5 into the passage 3, and another 35 enlarged opening 6 through which the water may flow into the lower opening 7 of the bubbling cup 8. The bubbling cup 8 consists of a hollow spherical bulb with an upper and lower opening 9 and 10, and a shank 11 projecting below into the enlarged bore of the valve member 1, the cup 40 shank having a passage connecting the openings 7 and 10. If the cup is made of metal it may be screwed into the bore of the valve member, as indicated; if of glass or porcelain 45 then it may be fastened in any suitable manner into a metal sleeve screwing into the bore of the valve member.

Between the shoulder 12 at the opening 6 of the valve member and the lower end of 50 the cup shank is a metal disk with a number of apertures to break the force of the water as it flows from the opening 6 into the opening 7 and thence out at the opening 9. At the lower end of the valve member 1 is an 55 ordinary tap or outlet 23 with an inlet or

port 14 somewhat below that of the port 4. On the valve member 1 where it projects below the barrel a thread 16 may be cut, on which a nut 17 may be screwed against the barrel end to hold the valve member snugly 60 in place or to set it open or closed if desired. Projecting from one side of the barrel is the intake pipe 5 before alluded to. This may be curved, as indicated, with a thread 65 18 and shoulder 19 to attach to a horizontal surface, or it may be straight, as indicated by the dotted lines 20 to attach to a vertical surface. A filter 21 of any ordinary form and material may be placed in the threaded end of the intake pipe.

The ports 4 and 14 are so placed with reference to each other and to the opening 5 that they cannot both face the opening simultaneously, but so that either may face it when the handle 2 is turned in the appropriate direction. Hence, if it is desired to use the faucet as a hygienic drinking fountain the handle is turned so as to cause the port 4 to face the opening 5; port 14 will then face the wall of the barrel, and will 70 be closed. If it is desired to use the faucet as an ordinary drawing-off outlet, the handle is turned so as to cause port 14 to face the opening 5; port 4 will then be closed. The handle may also be turned so that 75 neither port will face the opening 5, and then no water can flow. So that the faucet may be used as a bubbling drinking fountain or as an ordinary faucet, or the water may be shut off altogether, by merely turning the handle to its appropriate position. If the filter is in place, as indicated in the diagram, it will in no way interfere with the action of the faucet, as described, and a simple combination of a filter, a drinking 80 cup, and a drawing-off, or tap, faucet will 85 result.

As is well known the pressure in water mains varies in different localities, and the pressure in the same mains frequently varies 90 from time to time. Hence to maintain the fountain height in bubbling cups approximately constant, some method of regulating the pressure effect becomes desirable. This I accomplish by two methods; one a permanent adjustment, depending on the general average pressure of the water where the cup is to be used, and the other an adjustment that can be made quickly depending upon the temporary pressure of the 95 100 105 110

water. The amount of water flowing out of the cup and hence the height of the fountain depends upon the number and size of the apertures 22 in the disk 13. This disk 5 may readily be replaced, and one with apertures suitable in number and size to the average pressure may be used. If it is desired to regulate still further the flow it may be done by leaving more or less of the 10 port 4 facing the barrel wall and hence closed. And to cause this regulation to be less sensitive the port 4 may be horizontally elongated as indicated in Fig. 4, so that a given movement of the handle will cause 15 less variation in flow than if the port were circular.

It is evident that the angular distance between the ports 4 and 14, and between each port and the handle 2, may be varied 20 so as to make the handle throw from one port to the other more or less, as desired, and so as to place the handle when either port is used, in any desired direction. Any suitable stops, adjustable or otherwise, may 25 be placed on the faucet so as to stop the handle wherever desired either to obtain proper fountain height, or to facilitate throwing of the handle.

I claim as my invention:
30 A combination fixture of the character described, comprising a pipe having a longi-

tudinal bore and having a transverse vertical tapering passage intersecting said bore at the discharge end of the latter, a downwardly tapered valve member fitting in said 35 vertical passage and having exterior screw threads below said passage, a nut turned on said threads for preventing upward displacement of the valve member, said valve member having a port leading up through 40 its lower end and opening on the face of the valve member in the plane of said longitudinal bore, said valve member further having a port extending downwardly from its 45 upper end and terminating on the face of the valve member in the plane of said bore, a drinking cup mounted on the upper end of said valve member and communicating with the last mentioned port, said two ports opening on the side of the valve member at 50 different points, whereby the valve member may be turned to bring either point into registry with said bore or in position with neither of said ports in such registry, and a handle fixed to said valve member for rotating it.

In testimony whereof I affix my signature in the presence of two witnesses.

JOHN HETHERINGTON.
